UNITED STATES PATENT OFFICE.

HENRY C. OSBORN, OF CLEVELAND, OHIO.

CIRCULATING SYSTEM FOR AUTOMOBILES.

SPECIFICATION forming part of Letters Patent No. 752,856, dated February 23, 1904.

Application filed June 10, 1902. Serial No. 111,026. (No model.)

To all whom it may concern:

Be it known that I, HENRY C. OSBORN, a citizen of the United States, residing at Cleveland, in the county of Cuyahoga and State of Ohio, have invented certain new and useful Improvements in Circulating Systems for Automobiles, of which the following is a specification, reference being had therein to the accompanying drawings.

10 My invention relates to automobiles, and is especially well adapted for use in connection with the type propelled by gas-engines. It is well understood that in using gas-engines it is necessary to circulate water around the 15 engine-cylinder to reduce the excessive heat and prevent premature explosions of the gases, and it frequently happens in using automobiles of this class in cold climates that the 20 circulating water freezes, with disastrous effects to the circulating system. This leads to great annoyance and always occasions considerable delay in starting the machine.

The object of this invention is to provide a simple means for quickly putting the 25 circulating system intact in case of an accidental freezing.

The invention consists in a certain arrangement and combination of parts to be more fully described hereinafter and definitely set 30 forth in the claims.

In the drawings, which fully illustrate my invention, Figure 1 represents, in side elevation, somewhat diagrammatically an automobile to which my invention has been applied. 35 Fig. 2 represents a detail of the invention in longitudinal vertical section.

Referring to the parts by letters, A represents the body of an automobile in side elevation, carrying a gas-engine B, adapted to 40 propel the vehicle in the usual manner by means of the connecting-rod b and crank c, operating the shaft C, the sprocket-chain D affording means for rotating the rear axle. In applying my invention to such an automobile a small rotary pump E is provided 45 and preferably driven directly from the engine-shaft C, as indicated. A pan or reser-

voir F is carried by the vehicle, preferably on the lower side of the body toward the front, as indicated. This reservoir contains 50 circulating water and constitutes a radiator also for cooling the same. Within it is arranged a suction-nozzle G, the construction of which will be more fully described later. This nozzle connects by means of the pipe g 55 with the inlet-opening of the aforesaid rotary pump E. From the outlet-opening of the pump a section of pipe e leads the water to the engine-cylinder wall, through which it circulates in the well-known manner, finding exit 60 through the return-pipe H. This return-pipe is arranged so that it inclines downward toward the front of the vehicle, wherefore the water is adapted to drain by gravity in that direction, and its extremity is provided with 65 a downward extension h, which delivers the water within the reservoir F. In this manner while the machine is in motion water is continuously circulated about the engine-cylinder for the purpose mentioned. Referring especially to Fig. 2, it will appear that this nozzle 70 consists of a substantially cylindrical body having an inner tube or duct g', which passes from the bottom to the top of the same and connects at its upper extremity with the aforesaid suction-pipe g. In this manner an inner duct is formed, surrounded by a chamber g".

The exhaust-gases from the cylinder B pass rearwardly into the muffler K, which is of any suitable construction, whence they are led 80 by the pipe k toward the front of the vehicle. This pipe connects at its extremity, as indicated, with the aforesaid chamber g". An outlet-pipe g' is provided, which leads from this chamber and is adapted for carrying the 85 exhaust-gases to the open air. In this manner the exhaust-gases from the engine may be made to circulate through the chamber g", and if the water within the reservoir F should be frozen they quickly melt the ice in the 90 neighborhood of the suction-nozzle. The small amount of water which is produced in this manner is immediately drawn away by the pump, circulated about the engine-cylinder,

der, and returned, and as its temperature will be found to have been much increased with contact with the heated cylinder-wall it also lends its aid toward reducing the remaining ice within the reservoir. The pipe *k* is provided with a two-way cock *L*, adapted to direct the exhaust-gases either toward the suction-nozzle or to allow them to exhaust into the open air through the outlet-pipe *l*. This arrangement allows the operation of melting the ice to be discontinued as soon as it is no longer necessary.

It will be observed that the reservoir *F* is located at the lowest level of the circulating system and the piping and connections are so arranged that when the vehicle is standing idle the water of the system will drain into the reservoir.

What I claim is—

- 20 1. In an automobile, in combination, an engine adapted to propel the vehicle, a water-circulating system, a reservoir forming a part of said system and located at a lower level than any other point in said system, pipes leading to and from said reservoir, one of said pipes extending into said reservoir, and means for passing the exhaust-gases from said engine around said pipe extending into said reservoir, substantially as described.
- 25 2. In an automobile, in combination, a gas-engine adapted to propel the vehicle, a water-circulating system including a reservoir in which the water of said system may collect, a suction-nozzle through which the water from said reservoir may be drawn, and means for circulating the exhaust-gases from said engine around said nozzle, substantially as set forth.
- 30 3. In an automobile, in combination, a gas-engine adapted to propel the vehicle, a water-circulating system adapted to lead water around the cylinder-wall of said engine, a reservoir in said circulating system in which the water may collect, a suction-nozzle through which the water from said reservoir may be drawn, and means for circulating the exhaust-gases from said engine around said nozzle, substantially as set forth.
- 35 4. In an automobile, a gas-engine adapted to propel the vehicle, a water-circulating system adapted to lead water around the cylinder-wall of said engine, a pump adapted to maintain said water in circulation while said vehicle is in motion, a reservoir included in said water-circulating system and in which the water is adapted to accumulate, a suction-nozzle through which the water from said reservoir is adapted to be drawn and means for circulating the exhaust-gases from said engine around said nozzle, substantially as set forth.
- 40 5. In an automobile, in combination, an en-

gine adapted to propel the vehicle, a water-circulating system, including a reservoir in which the water of said system is adapted to accumulate, a pipe adapted to lead the exhaust-gases from said engine through said reservoir, an outlet for said gases directly into the outer air between the engine and said reservoir, and means for controlling the flow of the gases through said reservoir and through said outlet, substantially as set forth.

6. In an automobile, in combination, a gas-engine adapted to propel the vehicle, a water-circulating system adapted to supply water to the jacket of said engine, a reservoir forming a part of said system and located at a lower level than any other point in said system wherefore the water may accumulate therein, means for leading the exhaust-gases from said engine through said reservoir, and means intermediate of the engine and said reservoir for permitting the escape of said gases, substantially as described.

7. In an automobile, in combination, a gas-engine, a water-circulating system including a reservoir at a low level in said system wherefore the water may accumulate therein, a suction-nozzle within said reservoir, through which the water of said reservoir may be drawn, said suction-nozzle comprising an innerduct and a chamber surrounding the same, and means for leading the exhaust-gases from said engine through said chamber, substantially as set forth.

8. In an automobile, in combination, a gas-engine adapted to propel the vehicle, a water-circulating system adapted to lead water around the cylinder-wall of the said engine, a muffler receiving the exhaust, a reservoir at a low level and included in said circulating system, said reservoir being of such capacity as to contain all the circulating water of said system, and means for leading the exhaust-gases from said muffler through said reservoir, substantially as set forth.

9. In an automobile, in combination, a gas-engine adapted to propel the vehicle, a water-circulating system including a reservoir in which the water of said system may accumulate, a muffler into which the exhaust-gases of said engine may pass, a pipe leading from said muffler through said reservoir, a branch outlet connecting with said pipe and leading directly to the open air and a two-way cock adapted to direct the gases from said muffler to said reservoir or through said branch outlet, substantially as set forth.

10. In an automobile, in combination, a water-circulating system, a nozzle adapted to have the circulating water drawn there-through, means whereby the water may accumulate thereabout when not circulating,

and means whereby a fluid at a high temperature may pass around said nozzle, substantially as set forth.

11. In an automobile having a gas-engine and a circulating system including a reservoir, the combination of a nozzle extending into said reservoir, a pipe connecting said nozzle with the water-jacket of said engine, a casing around said nozzle, connections leading from

the exhaust-port of said engine to said casing, and a suitable outlet therefor, substantially as described.

In testimony whereof I affix my signature in presence of two witnesses.

HENRY C. OSBORN.
